UNITED STATES PATENT OFFICE

EDWARD R. SIMPSON, OF SAN BERNARDINO, CALIFORNIA

CONCUSSION SWITCH

Application filed December 27, 1924. Serial No. 758,331.

This invention relates to systems and means for protecting cashiers' cages and the like, and the invention has for an object the provision of a system which will automatically close doors, and lock cages, to prevent theft of any money in such cage or cages resultant upon the discharge of a firearm adjacent the cage or in its approximate locality, or upon bringing a firearm adjacent the cage 10 without discharging such firearm.

In practicing the invention I have found it expedient to provide a safety system for the use of cashiers which is so formed and constructed as to not only protect any cash within 15 in the cage and under the control of the cashier from being stolen, but likewise to prevent the cashier from being shot. I accomplish these desirable features by arranging novel forms of magnetic switches and 20 concussive switches adjacent the cage, as well as so arranging the main portion of the cage that the cashier may readily see the party in front of the cage and yet have the front of such cage so arranged that a discharge of a 25 weapon directly at the cashier would cause any bullet discharged from such weapon to not enter directly within the cage but to be deflected either upwardly or downwardly. Furthermore, a discharge of any such weapon 30 will operate the concussive switches to lock the cage doors, as well as any other doors such as the entrance doors upon a discharge of such weapon to trap the intruder. The magnetic switches will operate to close doors 35 and where desired, to drop a screen with great rapidity adjacent the wicket of the cage, when a weapon is brought in close proximity to such cage.

Other objects of the invention will appear as the description proceeds, and with the objects heretofore mentioned the invention consists in the novel and useful provision, formation, construction, association and inter-relation of parts, members and features, all as illustrated in certain of its embodiments in the accompanying drawings, described generally and finally pointed out in the claims.

In the drawings:

Figure 1 is a fragmentary and partly sectioned plan view, of a series of cashiers' cages,

such as used in banks, a main entrance doorway and likewise a safety deposit vault;

Figure 2 is a fragmentary enlarged view of the front of one of the cashiers' cages;

Figure 3 is a fragmentary vertical sectional view of the front of a cashier's cage shown in Figure 2;

Figure 4 is an enlarged fragmentary and cross sectional view of the shutters forming the front part of the cashier's cage;

Figure 5 is a detail plan view of a magnetic switch;

Figure 6 is a transverse sectional view of the magnetic switch shown in Figure 5;

Figure 7 is a fragmentary enlarged view of portions of the magnetic switch;

Figure 8 is a transverse sectional view of a concussive switch;

Figure 9 is a diagrammatic layout showing the switches and mechanism operated when such switches are closed;

Figure 10 is a fragmentary and partially sectional view showing an arrangement of the front of the cashier's cage, and various switch locations; and,

Figure 11 is a detail, partially fragmentary and sectional view of a shutter or door member adapted to be actuated to close a certain portion of the cashier's wicket.

Corresponding parts in all the figures are designated by the same reference characters.

Referring with particularity to the drawings, I have designated the improved system and means for protecting cashiers' cages by A, and reference is had to Figure 9 wherein it will be seen that in the embodiment of the invention shown such system A will include the following elements and features, either used singly or jointly, as vibration or concussion switches a, magnetic switches b, hand-operated switches c, door release mechanism d, trap-door mechanism e, curtain operating mechanism f, door lock means g, and audible and visual signaling means h, as well as relays j and k.

A typical cashier's cage B which may use the various elements embodying the invention, is shown in plan in Figure 1 and in elevation in Figure 2, as well as cross sectional views in Figures 3 and 4, and such cage B

will be described prior to describing the various other means entering into the invention. It may be said that a system of control is shown in Figure 9, while a portion of the means is shown in Figures 1 to 4 inclusive. It is essential that a bank cage be fully protected so that theft of money or other objects within the cage may not be successfully accomplished, or at least that hindrance be placed in the way of an intruder to render his capture a surety.

Referring to Figure 1 which is a typical floor plan of the average bank, we find a series of cashiers' cages or tellers' cages as they are sometimes termed, at 1, 2 and 3. The front entrance is shown at 4 and may have two swinging doors 5 and 6 to close such entrance. At 7 the usual safety deposit vault may be provided with a slide door 8 in the wall or wicket 9 to obstruct or permit entrance to the vault 7 when the vault door 10 is open. Certain of the elements or means shown in Figure 9 are shown in Figure 1 and designated in accordance with the letters previously given, and it will be noted that the visual or audible signals *h* may be adjacent the manager's office or the vice-president's desk, as indicated at 11, or at any other locality desired. The front wall or panel in front of the cages may be of ordinary construction and the same is designated as 12. The usual counter 13 is provided for each cage and as is customary, walls 14 separate the respective cages as well as back walls 15 to which are hinged doors 16 adapted to close off such cage or cages. It will thus be seen that access from one cage to the next adjacent cage is prevented, except by entering through the door 16 of the respective cages. The front portion of each cage above the counter portion is provided with the usual teller's pay wicket 17, and spaced uprights 18 and 19 are suitably anchored through the counter or to the counter and are approximately located in alignment with the respective walls 14. The pay wicket 17 would be approximately located in a central position between such uprights 18 and 19 and the space between the uprights 18 and 19 and the wicket 17 might be enclosed by sheet metal members 20 and 21. Immediately above such metal members 20 and 21, as well as the wicket 17 are shutter members designated generally as *m*. These shutter members are detailed in Figures 3 and 4 and each shutter may comprise two spaced glass members 22 and 23 separated by a flexible cushion 24 with ends 25 and 26 of the respective glass members 22 and 23 longitudinally anchored in channel members 27 and 28, which channel members at their ends are pivoted to the uprights 18 and 19 respectively. A second set of members designated generally by the numeral 29 are each provided with retaining means 30 associated with the members 23 of each respective

shutter member *m*, and at one side of one of the uprights or joined to an upright, as the case may be, is a toothed segment 31, there being a lever 32 carrying a dog 33 adapted for play over such toothed segment, the dog being received between any selected teeth, and the member 29 is pivoted to such lever as shown at 34, and thus movement of the lever will permit various angularities to be assumed by the shutter members relative to the front of the cashier's cage. It will be particularly noted that the shutter members *m* extend between the uprights 18 and 19. It will also be observed that the member 23 is not of as great a width as the member 22 in the showing, although they might be of the same width. The method shown, however, presents a more pleasing appearance exterior the cage, as the two channel iron members 27 and 28 respectively are in normal alignment transversely between the uprights 18 and 19. It will of course be understood that such uprights 18 and 19 may be of angle iron formation and that the pivot point and the point of jointure of the channel iron members 27 and 28 would be hidden from view exterior the cage. If the members *m* are formed of tough enough glass or other substance a bullet fired at each shutter members would be deflected upwardly and out of the top of the cage or stopped altogether. It would be practically impossible to shoot in straight path through the cage and hit the teller or cashier by firing at the shutters. Immediately behind the wicket 17 is a short shutter member designated as 35, which in all details is similar to the shutter members *m*, with the exception that it is only of a width slightly greater than the wicket member 17 (see dotted lines in Fig. 2).

The pay opening 36 of the wicket 17 is shielded rearwardly by a shield member *n* which may be formed of glass and which shield member extends beyond the marginal portions of the pay opening 36 and is held in position at an angle to the plane of wicket 17 bounding such pay opening, as illustrated in Figure 3 by means of a channel member 37 carried by an arm 38. This arm 38 is pivoted as at 39 to a portion of the wicket 17 and such arm is formed with a notch shown at 40 within which a dog 41 may be dropped for the purpose of holding the arm in the position shown in Figure 3. Thus such shield *n* may be raised upwardly by releasing the dog 41 from the notch. It will be noted that the counter 13 projects outwardly from the front of the cashier's cage and that such counter is provided with a ledge 42. On the inside of the cage and at the opposite edge portion of the counter, I have provided a wall 43 which extends longitudinally of such counter, and such wall where it extends above the counter is curved as shown at 44 at its upper extremity. Thus, if an intruder were to place a

weapon in front of the cage his hand would contact with the ledge 42 which would raise the weapon and if he attempted to fire through the opening 36 the bullet would be stopped by the wall 43, providing the bullet missed the shield *n*. If an intruder upon firing a shot saw that the bullet produced no effect he might shoot downwardly upon the counter top expecting the bullet to deflect upwardly, but to prevent such upward deflection of a bullet upon striking the counter top I have provided a cut-out portion 45 in such counter top and such cut-out portion is covered with yielding plate 46 which is readily penetrable by bullets or the like.

It will be noted that this yielding plate extends both outwardly and inwardly of the counter 13 relative to the front wall portion of the cage.

20 The other elements entering into the system of preventing theft designated by *A* will now be described in their relation to the means *B*.

25 The switch *a* is what is known as a concussion or vibration switch, and the same may consist of a shell or container 50 screw-threaded as at 51 for the reception of a cap 52 and such cap confines between itself and the rim of the container or shell a diaphragm

30 53 which is bulged as shown at 54. Joined to the diaphragm and at the approximate center of the bulged portion thereof, is a contact member 55, and in alignment with such contact member 55 and carried by the shell 50 is a further contact member 56. A suitable wire 57 connects the contact member 55 with a binding post 58 associated with the shell. Also carried by the shell is a spring-actuated plunger member 59 which projects

40 inwardly of the shell adjacent the diaphragm 54 and which plunger externally of the shell is provided with a finger-piece 60, there being a coil spring 61 surrounding a portion of the plunger between the finger-piece 60 and an

45 outer surface portion of the casing. Excessive vibration or concussion such as would result from the discharge of a weapon will spring the bulged part of the diaphragm into the dotted line position shown in Figure 8 at 62, at which time the contact members 55 and 56 would meet. The diaphragm may be restored from the dotted line position to the full line position of Figure 8 by pushing inwardly upon the finger-piece of the plunger

55 59.

The magnetic switches *b* may include a shell or casing 63 provided centrally with a compass needle pivot 64 upon which is a compass needle 65 and such compass needle is provided at its north and south pole ends with brushes 66 and 67, there being one brush for each end, and an insulating disc 68 is likewise carried by the base portion of such casing or shell 63, and mounted on such base portion 68 are two spaced and diametrically

opposite segmental contact members 69 and 70, such contact members being formed so as to have two inclined surface portions 71 and 72 with the peak or the meeting zone of such inclined portions as 73, at approximately the median length of such contact members. The means *f* may comprise a solenoid 80, the plunger of which carries a rack 81, the teeth of which are in mesh with a pinion 82 attached to the shaft of a drum 83.

Referring again to Figure 3, the upper extremity of the front wall is formed as shown at 84 to confine a roll shade or curtain 85 which extends transversely between the uprights 18 and 19. This shade or curtain may be formed of steel chain or the like or may be an ordinary curtain, and such curtain is operated through the medium of a curtain cord 86 associated with the same and with the drum 83. Thus operation of the solenoid 80 will draw the solenoid plunger within the coil of the solenoid pulling the rack downwardly to rotate the pinion and thus wind the curtain cord 86 upon the drum 83. It will be noted that this curtain when drawn will be in front of the shutter member *m* and would of course be very disconcerting to an intruder when it suddenly passed downwardly in front of such shutters to obstruct the view. The door release *d* may comprise an arm 90 pivoted as at 91 either to the floor or to the wall by suitable means, and which arm is notched as shown at 92 to embrace opposite side portions of the door. A solenoid 93, provided with a plunger 94, is coupled with a portion of the arm as shown at 95, and when the plunger is energized, the same will draw the arm 90 downwardly to release the door, but when not energized, a spring 96 will normally hold the plunger 94 outwardly from the solenoid so that the arm will hold the door open.

Another feature of the invention resides in the means *e*, which has been termed a trap-door and this member is detailed in Figure 11. The said means may include a shutter or door comprising a flexibly bound screen, the flexible binding being designated as 100, and the screen as 101, and such screen may be formed of steel mesh or may be solid as desired. However, for the purpose of this invention it is preferable that it be formed of steel mesh. One edge of such shutter or door is rigid and not flexible, as shown at 102 and this part is pivoted to a lever 103 which is directly adjacent the pay opening 36 of the wicket 17. A cord 104 connects with an end of such lever 103, it being noted that the lever projects through the counter 13, and such cord is passed over a grooved wheel 105 and connects with a rod 106 formed with a notch 107, the rod being received within a guide member 108 and a coil spring 109 connects with the rod and with a member 110. A solenoid 111 is provided with a plunger 112

112 which is keyed within the guide 108 as indicated at 113, and provided with a beveled extremity 114 adapted to be received in the notch 107 to maintain the rod in the position, as illustrated in Figure 11. However, when the solenoid is energized the plunger would be drawn inwardly, the rod 106 released, being drawn downwardly by the spring 109 which is in tension to swing the shutter or door *o* about its pivot point, and across the space occupied by the wicket 17.

The door lock *g* is conventional and may comprise a solenoid 115 having the usual plunger 116 normally forced outwardly from said solenoid by a spring 117 so that the said plunger will engage a bolt 118, the said bolt being notched as at 119 for reception therein of an end of the bolt. Such bolt is normally urged outwardly of a casing 120 by a spring 121. Thus when a door as indicated at 122 is in the position illustrated, and the solenoid coil energized, the plunger 116 would be drawn inwardly and the bolt 118 shot to lock 25 the door. The hand switches *c* may be of any form and the same will not be described. A relay *k* may be provided for ensuring that current would be supplied to the various circuits, and such relay consists of a contact arm 30 130 joined to a core 131 received in a solenoid coil 132. A source of current such as a generator is indicated at 133 and a storage battery or other source of current supply indicated at 134. Likewise there are provided 35 spaced contact members 135 and 136 arranged in pairs. The circuit from the source of supply 133 passes to one of the contacts 136, likewise through the coil 132 to a ground and its opposite contact 136 coupled through a 40 resistance with a further circuit member 137. Thus when electricity is being supplied by the member 133 the arm 130 contacts with the members 136, but if the current should be from the source 133, a spring 139 would 45 draw such arm 130 against the contacts 135 and the circuit would be completed from the source of supply 134.

The operation, uses and advantages of the invention are as follows:

50 The precise arrangement and placement of the vibration and magnetic switches will depend upon the general structural features of the cages, but in the showing of the drawings I have arranged the vibration or concussion switches in the following locations,— vibration switches are located rearwardly and associated with the members 20 and 21; back of the front wall or panel 12; adjacent the wicket 17, and above the pay opening 36. 55 See the positions in Figure 2. A vibration switch may also be placed on the wall 43 (see Fig. 3).

The magnetic switches *b* are preferably placed beneath the flexible member 46 of the counter top (see Figs. 1 and 3).

It is understood that the front door members 5 and 6 are provided with suitable door closers 140, and that the door release members *d* would normally have the notched portions 92 of their arms 90 engaging such doors 5 and 6 to hold the same open. It is customary to have the doors 16 of the cages swing closed, suitable closers or springs being utilized for this purpose, and a door lock *g* is provided for locking such doors when closed, responsive to energizing the solenoid 115. The door 8 is usually supported on grooved wheels which run on an inclined railing so that the door closes under influence of gravity. When the door is closed the same might be locked closed by the means *g*.

Referring to Figure 9 it will be seen that the circuit or lead 137 connects with a contact 141 of the relay *j*, such relay comprising a coil 142 within which is a movable core 143 carrying a contact arm 144. Another contact member 145 is spaced from and in normal alignment with the contact member 141 so that when the coil 142 is energized the core 143 will be drawn inwardly and the arm 144 will bridge the space between the contacts 141 and 145 and touch the same. A lead 146 connects with the contact 135 and with the lead 137 and such lead 146 is connected to one terminal of the vibration switches *a*, by a lead 147, it being noted that there is a series of such vibration switches in the showing of Figure 9 connected in parallel. The opposite terminals of such switches connect with a lead 148 and which lead is connected with a terminal of the coil 142 of the relay *j*, and likewise with the contact member 145, and then such lead connects with a terminal of switches *g*. The magnetic switches *b* are connected in parallel by leads 149 and 150, the lead 149 connecting with the lead 146 and the lead 150 with the lead 148. The hand-operated switches *c* are likewise connected in parallel by leads 151 and 152, the lead 151 connecting with the lead 146 and the lead 152 with the lead 148.

The switches *g* may be hand-operated and normally closed, and a lead 153 connects with a terminal of such hand-operated switches *g*, and with a lead 154; the lead 154 connects with terminals of the following coils, namely, 115, 93, 111, 80 and with a terminal of the visual or light means and audible means *h*. Opposite terminals of such means *h* as well as the coils 115, 93, 111 and 80 are grounded. It is to be noted that one terminal of the relay coil *j* is grounded, as is likewise a terminal of the generator 133 and a terminal of the battery 134.

If we assume that the bank is held up and a revolver or pistol passed through the wicket opening 36 or one of the cages, as shown in Figure 10, the revolver being designated as 160, the magnetic switches would be operated for the reason that the steel in the revolver

would tend to rotate, when brought in close proximity to the magnetic switches, the compass needle 65 and cause the brush members to make contact with the segments 69 and 70 and complete an electrical circuit, which would operate the visual and audible signals *h*, drop the curtain forming a part of the means *f*, permitting a releasing of the doors by the door release means *d*, and locking such doors when closed by the door lock *g*, as well as swinging the means *e* which includes the trap door across the wicket opening, this swinging of the trap door being illustrated in dotted lines at *f*. The flexible binding 100 would assume the dotted position illustrated at 161 holding the hand or arm of the intruder if the hand or arm had been passed through the wicket opening 36. If an intruder, when this occurs should attempt to shoot, the bullet would be prevented from doing damage by striking either the shield *n* or the wall 43 of the counter. If instead of bringing the pistol in close proximity to the counter where the magnetic switches are located, the intruder should fire the pistol, for the purpose of frightening members of the bank staff to raise their arms so that the hold-up might be complete, the concussive effect in close proximity to the cages would operate one or more of the concussive switches, forcing the diaphragm or diaphragms inwardly from the position in full lines of Figure 8 to the dotted line position of such figure to complete an electrical circuit to operate the members previously enumerated.

To restore the various parts to neutral position the switches *g* are opened and in this connection may be hand-operated switches. This will of course open the circuit, stop the audible signal and visual signal from operating, and allow restoration of the trap door to its upright position, as illustrated in full lines of Figure 11 and permit the doors to be unlocked and again held open as well as permit the curtain to be rolled above the shutters *m*, as illustrated in Figure 3. It will likewise be noted upon reference to both Figures 2 and 3 that port openings 162 are provided in the front panel or wall 12 for each cashier's cage and which openings are beveled rearwardly and terminate in narrow slits in the front of the wall 12. This construction is similar to the general construction of battleship port holes. It would be practically impossible for a person to shoot through such holes exterior the cage but to fire a weapon rearwardly of such panel and outwardly from the cage would be an easy matter.

The magnetic switches are easily restored to a neutral position by means of a small reset coil 163 shown in Figure 5 and which reset coil is operated through the medium of a suitable energizing means 164 in series with a switch 165. It is possibly unnecessary

to state that the magnetic switches are so arranged that the compass needle may assume its normal north and south position with the segments arranged practically at a right angled position to the longitudinal position or north and south position of the compass needle.

It is obvious that various changes and modifications and variations may be made in practicing the invention, in departure from the particular showing and means illustrated in the drawings, without departing from the true spirit of the invention.

Having thus disclosed my invention, I claim and desire to secure by Letters Patent:

1. In a concussion switch, means acting responsive to air concussion to move to a determined position, an electrical switch adapted to be closed when the means assumes said predetermined position, and manually operated means for opening said electrical switch.

2. In a concussive switch, a casing, a diaphragm secured to said casing, said diaphragm being provided with a bulged portion normally extending outwardly from the casing, an electrical contact member carried by said bulged portion of the diaphragm, and a second electrical contact within said casing, said diaphragm acting responsive to air concussion to move the bulged portion inwardly to bring the electrical contacts into closed position.

3. In a concussive switch, a casing, a diaphragm secured to said casing, said diaphragm being provided with a bulged portion normally extending outwardly from the casing, an electrical contact member carried by said bulged portion of the diaphragm, a second electrical contact within said casing, said diaphragm acting responsive to air concussion to move the bulged portion inwardly to bring the electrical contacts into closed position, and means for breaking the electrical contacts and restoring the bulged portion of the diaphragm to its outwardly facing position.

4. In a concussion switch, means acting responsive to air concussion to move to a determined position, an electrical switch adapted to be closed when the means assumes said predetermined position, and means for opening said electrical switch.

5. In a concussive switch, a casing having an open end portion, a diaphragm closing said open end portion, electrical contact means within and included between the casing and diaphragm; said diaphragm moving responsive to air concussion upon the surface thereof to close said electrical contact means.

In testimony whereof, I have signed my name to this specification.

EDWARD R. SIMPSON.

130
